UNITED STATES PATENT OFFICE.

WILLIAM A. CAMPBELL, OF GRENADA, MISSISSIPPI.

LOADING AND UNLOADING DEVICE.

1,359,790.

Specification of Letters Patent. Patented Nov. 23, 1920.

Application filed June 8, 1920. Serial No. 387,443.

To all whom it may concern:

Be it known that I, WILLIAM A. CAMPBELL, a citizen of the United States of America, and resident of Grenada, in the county of Grenada and State of Mississippi, have invented certain new and useful Improvements in Loading and Unloading Devices, of which the following is a specification.

10 This invention relates to loading and unloading devices and particularly to an extensible mast arm, the said invention having for its object the provision of novel means for loading and unloading box cars and other closures, and the said device is also of utility in storehouses where loads are to be taken into the storehouses and placed at remote spots from the door. In fact, the utility of the device is manifold, 20 and I do not wish to be limited with respect to its application.

A further object of this invention is to produce an arm of the character indicated which can be extended for the purpose of receiving or delivering a load and which can be restricted in length so that it can be swung into an opening such as a door and again extended or projected to deposit the load at a spot remote from the door or opening.

30 A still further object of this invention is to produce a device of the character indicated which has adjustability vertically and in which the adjustment can be speedily attained.

With the foregoing and other objects in view, the invention consists in the details of construction and in the arrangement and combination of parts to be hereinafter more 40 fully set forth and claimed.

In describing the invention in detail, reference will be had to the accompanying drawings forming part of this specification wherein like characters denote corresponding parts in the several views, and in which—

Figure 1 illustrates a view in elevation of the mast arm and parts associated with it;

Fig. 2 illustrates a longitudinal sectional view of a fragment of the said mast arm, and

Fig. 3 illustrates a sectional view of the mast arm on a line corresponding with the line 3—3 of Fig. 2.

55 In these drawings 5 denotes an upstanding bar or shaft which constitutes anchor-

ages for installing the device, and this shaft is, of course, to be secured in an upright position in any appropriate manner. As, however, the manner of securing it is immaterial and does not constitute a part of the invention, the details of this arrangement are not disclosed. The collars 7 and 8 are movable vertically of the shaft and constitute bearings which are engaged by 60 anti-friction members 9, such as balls, which may rotate in raceways formed in the faces of the said collars. The collars also have apertured lugs or ears 10 and 11 respectively. The walls of these apertures are 65 threaded to engage a screw 12 which screw is rotatably mounted in heads 13 and 14 at opposite ends of the shaft 5. The screw may be provided with an operating hand wheel 15 so that the collars may be raised 70 and lowered for adjusting the position of the operating parts of the mast arm, as will presently appear.

There is a short arm 16 which has a head 17 which is apertured and rotatably mounted on the shaft 5 between the bearings, and the outer end of the arm has plates 18 and 19 secured to it, the said plates projecting beyond the end of the arm and having coinciding apertures 20 to receive a pivot 21. 80 The telescopic portion of the arm comprises an inner section 22 having an apertured head 23 mounted on the pivot 21 and a series of telescopic sections 24, 25, 26 and 27 or such number as requirements of practice may dictate. Each of the projecting telescopic sections has at its outer end an enclosing ring 28, the aperture of which is slightly larger than the diameter of the section which moves with relation to it, and this ring 28 constitutes an abutment to limit the movement of a bearing ring 29 which is within the said telescopic section. The said bearing ring 29 has a plurality of apertures such as 30 in which anti-friction balls 90 31 are seated, the said balls being of a diameter greater than the thickness of the bearing ring so that the peripheries of the balls travel on the inner surface of the larger section and the outer surface of the 100 smaller section which telescopes with relation to the larger section. The said smaller section has on its inner end, an abutment ring 32 which is adapted to strike the inner end of the ring 29 as the telescopic section 110 is moved outwardly, carrying with it the bearing ring so that the outwardly extend-

ing telescopic section is rigidly held by reason of the fact that there are anti-friction balls at the outer end of the bearing ring as well as at the inner end thereof, and the outwardly projecting telescopic section is supported so that lost motion is prevented, and the arm as a whole when extended will be a comparatively rigid structure capable of sustaining weight and carrying said weight as the sections are moved in and out during its operation.

I claim:

1. In a loading and unloading device, a shaft, an arm oscillatably mounted with relation to the said shaft, telescopically arranged members, means for pivotally connecting the innermost of the said members to the said arm, anti-friction members interposed between the smaller and larger sections, means on each larger section for limiting the movement of the anti-friction device, and means on each smaller section for

engaging the said anti-friction device for limiting the movement of the said smaller section.

2. In a loading and unloading device, a shaft, collars slidable thereon, means for holding the collars in spaced relation to each other and for moving them simultaneously on the shaft, an arm having a head mounted to oscillate on the shaft, plates carried on the outer end of the arm, the said plates being in spaced relation to each other, telescopically assembled members having their inner end pivotally connected to the said plates, anti-friction rings interposed between the telescopic sections, anti-friction members rotatably mounted in the walls of the said anti-friction rings and adapted to hold the telescopic members in spaced relation to each other, and means for communicating the motion of the telescopic members to the said anti-friction rings.

WILLIAM A. CAMPBELL.
